ARMATURE RECUTTING TOOL

Allen Burrows, Brockton, and Walter H.
Rhindress, Braintree, Mass.

Application August 9, 1937, Serial No. 158,062

2 Claims. (Cl. 82—4)

This invention relates to tools particularly adapted for cutting or trueing armatures of generators and similar devices which comprise a shaft which projects through and carries an armature including a commutator which consists of a cylinder, the curved surface of which is formed of strips or sections of copper or other good conducting material separated by strips of mica or other insulating material. When such commutators of armatures are worn down by the brushes, it is desirable, especially when they come from automobiles, that the whole device should be taken out with the armature on the shaft and to cut the armature cylinder in a new and perfect circle.

This tool is of such a character that when such a generator is taken out, it can be held in any ordinary vise with the armature and shaft sticking out and this tool can be quickly attached to the projecting shaft in such a manner that a cutter can be quickly adjusted and can then be turned by a hand wheel so that it cuts spirally around the curved surface of the armature progressing all the time until the cutting is entirely finished. It can then be used in such a way that the cutter is caused to travel parallel with the axis instead of circumferentially to cut down the isinglass or other insulations to the desired depth.

This tool can be used successfully with any generator, starter motor or other electrical machine in which there is a cylindrical armature commutator carried by a shaft which sticks out from it with a smooth, cylindrical end. Instead of centering such a shaft and commutator and revolving against a stationary tool, we hold the device in a vise or in any other kind of holder with the shaft and commutator sticking out and then attach this tool to the shaft, after which part of the tool revolves, carrying the cutting element.

We use a cylinder which we affix to the shaft and provide a rider slideable on this cylinder and a turnable member which engages the screw threads in the cylinder and which is detachable from the rider. By using a rider and turnable member detachably locked together, they do their cutting together, but when the cutting is finished, they can be separated, the turnable member being quickly spun back out of the way and the rider with the cutting member can be slipped back parallel with the axis and without revolving the cutter backward in a spiral, a procedure which is objectionable.

In the drawings,

Fig. 1 is a front elevation of our tool in position operating on an armature commutator of a generator which is held in place by a vise on a bench.

Fig. 2 shows in section the various parts which make up the tool.

Fig. 3 is a vertical section on a plane through the shaft and axis of the tool.

Fig. 4 is an enlarged sectional view on the line 4, 4 in Fig. 1 looking in the direction of the arrow. 10

Fig. 5 is a sectional view on a vertical plane through the axis of a modification of the cylinder.

Fig. 6 is a view similar to Fig. 3 of another modification.

Fig. 7 is an isometric view of a split bushing 15 such as we use, the taper being exaggerated.

Fig. 8 is a front elevation showing the rider disconnected from the hand wheel and the manner in which it cuts the insulation.

Fig. 9 is a view similar to Fig. 3, on a larger 20 scale, showing a modified form.

In the drawings, G represents a generator such as is used in automobiles. This generator is shown in Fig. 1 as being held in an ordinary vise V on bench L in such a manner that the armature and commutator M and its shaft S project beyond the bench. 25

N is a split bushing or clamp of the tapering type. The split is indicated by 2 and the cylindrical hole through it which engages shaft S is indicated by 3 while the tapered surface is indicated by 22.

This bushing N enters a tapered hole 4 in the supporting cylinder P which, as shown, is provided with the two holes 44, 44. Holes 44, 44 are so located that they are at the end of bushing N when it is in place. Bushing N can be pressed or tapped in place in hole 4 and when it is desired to disconnect them, a rod or chisel can be pushed in through one of the holes 44 and the bushing N loosened from the hole 4. 35

At the other end of the cylinder P is an internally threaded hole 5, the threads corresponding with the threads 6 on a screw shaft 7 carried by and fixed to a hand wheel H as by a pin 8. As shown, the hub D of wheel H has in one face 20 a hole 129 into which the end of cylinder P can enter with a smooth running fit, but the axis of screw shaft 7, cylinder P, bushing N and shaft S must coincide. As hand wheel H is turned by 50 handle K, the screw shaft 7, entering cylinder P, causes hub D to move towards the commutator M and as it turns, it moves spirally, from the position shown in full lines to that shown in dotted lines in Fig. 1.

B is a rider through which is a hole 12 of just the size to make a smooth, running fit with the outside of cylinder P. Radially projecting from the end nearest wheel H is a locking pin 9 which can be engaged and disengaged by a latch 19 carried by the hub D of wheel H. As shown, this latch includes a hook member 29, spring 30 and handle 31.

By pushing handle 31 and hook 29 in from face 10 20 and bringing hub D and rider B together and turning them until pin 9 and hook 29 engage, spring 30 will hold the parts quickly detachably together.

Rider B has a projection 40 through which is 15 a carrier recess 41 parallel with its axis. V is a cutter holder in recess 41 and, as shown, is pivoted at 45 and provided with the adjusting screws 46 and 47 by which it can be adjusted radially. Its other end is split at 48 to receive 20 a cutter or cutter tool T which is held in place by a tightening bolt 49.

In doing the cutting, the cutter, cutter holder, rider and handwheel or turnable member move 25 forward spirally together but when the cutting 30 is finished, the latch 19 is released from pin 9 when the handwheel can be spun backward very quickly on the threads 5 and 6, after which the cutting tool, cutter holder and rider can be slipped back on cylinder P. The cutting tool T, 35 preferably at one end 50, has a cutting edge which can be used in cutting around the surface of the commutator and at the other end 51, a narrower cutting edge which can be used to cut the insulation when the parts are unlocked, as shown in Fig. 8. To do this cutting, the rider separated from the hub D, can be and is pushed back and forth axially on the cylinder P.

The wheel and hub can remain in place, as 40 shown by the full lines in Fig. 8. The cutting tool T is reversed to bring the narrow cutting end 51 in position to enter the space between the copper strips. The tool is so adjusted that this end 51 enters to the right depth and the rider and the tool are then moved by hand from the dotted position to the full line position, thus 45 cutting down the insulation to the desired depth below the surface of the conducting elements.

Instead of a split tapered bushing such as N at the end of a cylinder such as P, we might 50 use a clamp O located in a hole 60 in the end of a cylinder V, similar to P, except that the shaft hole 61 which is concentric with hole 60 would be of just the size to fit the end of shaft S. As 55 shown, clamp O has two or more jaws such as 63, 63 projecting from the end of cylinder V which snugly fit shaft S, and are threaded on the outside with a slightly tapering thread 64 so that the ring nut 65 can be screwed out on them, thus tightening jaws 63 on shaft S to prevent 60 it from turning with the hand wheel and rider.

As shown in Fig. 6, I might use a cylinder such as C having at one end a tapered hole 74 or a bushing and at the other end 75, instead of inside threads, having the outside threads 71 which 65 engage internal threads 72 on the hub 73 of a hand wheel 70. When this hand wheel 70 is

turned, it moves a rider such as R in the same way as in the first described construction.

In Fig. 9, we show several modifications embodying the same principle. In some cases where there is a very long armature shaft such at 83, 5 we find it desirable to make the cylinder 80 threaded inside a hub such as 81 with a hole 82 entirely through it and of a size to permit the entry of shaft 83.

In this view also is shown the rider 84 as an 10 integral part of the hub 81. As with this construction the rider can not be separated from the hub and moved axially to cut the insulation between the metal strips of the commutator, the cutting tool, such as 85, has only a transverse 15 cutting end shown at 95.

In this construction also, the pivot 86 for the cutter holder 87 is at the end opposite tool 85 and the adjustment is made by means of a threaded post 88 around which is a compression 20 spring 89 which tends to lift the cutter holder.

Thumb nut 90 works against the spring 89 and when the right adjustment is secured, a set screw 91 in the side holds the parts in rigid adjustment.

The supporting cylinder can be smooth on the outside as P, part threaded as C or 80, and detachable from or integral with the turnable member such as the wheel and hub.

We claim:

1. In a tool for recutting commutators of armatures which are mounted on a shaft; the combination of a supporting cylinder having at one end means to attach it to the shaft and at the other end an internally threaded hole with 35 the axes of the attaching means, the shaft, the cylinder and the hole coinciding; with a rider 40 slidable and revoluble on the cylinder and provided with a locking pin and a cutter carrier recess; a hand wheel which carries a screw shaft 45 in engagement with the threaded hole in the cylinder and a locking latch in engagement with the locking pin; and a cutter holder pivoted in the recess and including means to adjust it radially and to hold it in place and means to hold a cutter in a position beyond the holding cylinder.

2. In a tool for recutting commutators of armatures which are mounted on a shaft with a smooth projecting cylindrical end; the combination of a supporting cylinder having at one 50 end clamp means to fix it to the shaft and at the other end an internally threaded hole with the axes of the attaching means, the shaft, the cylinder and the hole coinciding; with a rider 55 axially slidable and revoluble on the cylinder and provided with a locking pin and a cutter carrier recess; a hand wheel which carries a screw shaft in engagement with the threaded hole in the cylinder and a locking latch in engagement with the locking pin; and a cutter holder pivoted in the 60 recess and including means to adjust it radially and to hold it in place and means to hold a cutter in a position beyond the holding cylinder.

ALLEN BURROWS.

WALTER H. RHINDRESS.
